ATTORNEY.

INVENTOR

UNITED STATES PATENT OFFICE.

LEWIS A. HAWKES, OF MERCHANTVILLE, NEW JERSEY, ASSIGNOR TO C. HOWARD HUNT PEN COMPANY, OF CAMDEN, NEW JERSEY, A CORPORATION OF NEW JERSEY.

PROCESS OF MAKING PENS.

1,365,318.

Specification of Letters Patent. Patented Jan. 11, 1921.

Application filed April 6, 1920. Serial No. 371,582.

To all whom it may concern:

Be it known that I, LEWIS A. HAWKES, a citizen of the United States, residing at Merchantville, county of Camden, and State 5 of New Jersey, have invented a new and useful Improvement in Processes of Making Pens, of which the following is a full, clear, and exact description, reference being had to the accompanying drawings, which form 10 a part of this specification.

My invention relates to the manufacture of pens and more particularly to those types of pens having distorted points, such as, for example, ball pointed and turned up pointed 15 pens.

Heretofore, in the manufacture of ball pointed and turned up pointed pens, it has been the practice to fabricate the pen in the usual manner, involving cutting out the 20 blank or blanking, piercing or slotting, annealing, raising or shaping, hardening and tempering, grinding, slitting to form the nibs, and finally punching the point with a suitable tool to produce the ball point or 25 turned up point, as the case may be, each step being a separate operation.

The ball pointing, or similar operation of distortion of the point, results in great waste of material and time due to the fact that the 30 distortion of the point, after tempering and slitting, often causes the metal to crack or clip, thus spoiling the otherwise finished pen. If the temper is drawn out to such an extent as to avoid cracking, the pen is found to be 35 insufficiently tempered and the deleterious effect of distorting the separate nibs, formed by the slitting, is not reduced.

In accordance with my invention, I eliminate the separate point-distorting step and 40 distort the point after the annealing step and coincidently with the shaping of the blank, after which the pen is hardened, tempered, and slitted in the usual manner. Thus the distortion of the point is accomplished when it is soft and before the nibs 45 are formed, with the result that the number of pens spoiled is greatly reduced and the loss, from those which are spoiled, is minimized, due to the fact that the pen has 50 passed through relatively few operations and has had comparatively little labor expended on it. By virtue of my invention, therefore, I not only eliminate a complete 55 operation in the process of manufacture, but

the actual waste in units is greatly reduced 55 and the loss due to the wasted units is rendered negligible, compared to that of present methods.

I will now proceed to describe mechanism, suitable for carrying out the process 60 embodying my invention, with reference to the accompanying drawings, in which—

Figure 1 is a perspective view of a ball pointed pen.

Fig. 2 is a perspective view of a turned 65 up pointed pen.

Fig. 3 is a plan view of a pen blank.

Fig. 4 is a plan view of the blank shown in Fig. 3 after the piercing or slotting operation.

Fig. 5 is a plan view of a shaping die and guides, with the blank shown in Fig. 3 indicated by dotted lines.

Fig. 6 is a side elevation, partly in section, of a shaping die and punch, with the 70 blank in position for shaping.

Fig. 7 is a cross-sectional view of the subject of Fig. 6.

Fig. 8 is a plan view of a shearing device and guides, for slitting the pen, with the 80 upper shear removed.

Fig. 9 is a side elevation, partly in section, of the shearing device.

Fig. 10 is a cross-section of the shearing device.

The blank *a*, formed by stamping or cutting from a strip of metal stock, is pierced to provide the slot *b* and then annealed. After being annealed, the blank is shaped and the point distorted, to make a pen *s* 90 having a ball point *h*, for example, in a raising or shaping die. The shaping die *c* is cut out to the desired shape of the pen and provided with a pin *d*, which protrudes above its surface at a point adjacent the 95 position of the extreme point of the pen, when in the die. Guides *e*, suitably mounted and made adjustable, are provided to properly position the blank in relation to the die.

A suitably driven punch *f*, conforming to 100 the shape of the die and provided with a recess *g* opposed to pin *d*, is adapted to press the blank *a* into the die, thus raising or shaping the blank and at the same time distorting it to provide the ball point *h*, 105 through the action of pin *d*, in pressing a portion of the blank, adjacent the extreme point, into recess *g*.

The raised or shaped blank is then hardened, tempered and ground. After the grinding operation, the nibs are formed by slitting on a line running from the point 5 to the slot *b*. The slitting operation is accomplished by placing the pen between a pair of shears *j* and *k*, the blades of which are provided with irregularities to accommodate the ball point. The lower blade *j* 10 is provided with a recess *l*, while the upper blade *k* is provided with a corresponding downward extension *m*. A suitable rest *n*, for the pen, is placed adjacent the end of the shears and a pair of guides *o* and *p* are 15 placed on opposite sides to properly position the pen for slitting, the guide *o* being yieldingly held by means of a spring *q*, which permits the guide to be depressed by the upper blade during the actual slitting.

20 The above mechanism with obvious modification is likewise adapted for the production of a pen having a turned up point *r*.

It will be obvious that my invention is applicable to pens having any type of point 25 involving shaping or distortion of the metal, and it will be understood that I do not limit myself to the production of ball pointed or turned up pointed pens.

The apparatus described conforms to what 30 is known in the art, except that the shaping die *c* is provided with a pin *d*, the punch with a recess *g*, and the shears with an extension *m* and a recess *l*. The practice of my new process however does not require

the employment of apparatus of any particular construction.

Having now fully described my invention, what I claim and desire to protect by Letters Patent is:

1. The process of making specially 40 pointed pens which comprises shaping the blank and distorting the point in one operation and in a subsequent operation forming the nibs by slitting the pen through the thus distorted point.

2. The process of making specially pointed pens which comprises subjecting an annealed and slotted blank having a solid pointed end portion to pressure to shape the blank and impart to the point the characteristic distortion which it is designed the finished pen shall have, and subsequently forming the nibs by shearing the pen along a longitudinal center line extending through its distorted point into the front of its slot. 55

3. The process of making specially pointed pens which comprises cutting out the blank, slotting the blank, then annealing the blank, then simultaneously shaping the blank and distorting the point, then 60 hardening and tempering the shaped and slotted blank, and then slitting it along a longitudinal center line extending from the front of the slot through the distorted point.

In testimony of which invention, I have 65 hereunto set my hand, at Camden, N. J., on this third day of April, 1920.

LEWIS A. HAWKES.
